US00D909268S

(12) **United States Design Patent** (10) Patent No.: **US D909,268 S**
(45) Date of Patent: **** Feb. 2, 2021**

(54) **ARMREST FOR A VEHICLE SEAT**

(71) Applicants: **Anthony Harcup**, Virginia Water (GB);
Richard Peter John Nicholas, London (GB); **Brian Ward**, Noah Bridge (GB)

(72) Inventors: **Anthony Harcup**, Virginia Water (GB);
Richard Peter John Nicholas, London (GB); **Brian Ward**, Noah Bridge (GB)

(73) Assignee: **Ipeco Holdings Limited**

(**) Term: **15 Years**

(21) Appl. No.: **29/655,004**

(22) Filed: **Jun. 29, 2018**

(30) **Foreign Application Priority Data**

Jan. 5, 2018 (GB) 004595429-0002

(51) **LOC (13) Cl.** **12-16**

(52) **U.S. Cl.**

USPC **D12/195**

(57) **CLAIM**

The ornamental design for an armrest for a vehicle seat, as shown and described.

DESCRIPTION

FIG. 1 is an isometric view of an armrest for a vehicle seat showing, in particular, the ornamental design thereof.

FIG. 2 is a front end view of the armrest for a vehicle seat of FIG. 1.

FIG. 3 is a rear end view of the armrest for a vehicle seat of FIG. 1.

FIG. 4 is a left side view of the armrest for a vehicle seat of FIG. 1.

FIG. 5 is a right side view of the armrest for a vehicle seat of FIG. 1.

FIG. 6 is a top plan view of the armrest for a vehicle seat of FIG. 1; and,

FIG. 7 is a bottom plan view of the armrest for a vehicle seat of FIG. 1.

1 Claim, 7 Drawing Sheets
